JIG BLOCK FOR HAND-HELD SHEARS

John R. Mason, Los Angeles, Calif., assignor to Dracon
Industries, Chatsworth, Calif.

Filed Apr. 2, 1971, Ser. No. 130,878

Term of patent 14 years

Int. Cl. D8—99

U.S. Cl. D8—71

FIG. 1 is a perspective view of a jig block for hand-held shears, showing my new design.

FIG. 2 is a different perspective view thereof;

FIG. 3 is a side elevation view thereof;

FIG. 4 is an end elevation view thereof;

FIG. 5 is a top plan view thereof;

FIG. 6 is another end elevation view thereof;

FIG. 7 is a bottom plan view thereof; and

FIG. 8 is another side elevation view thereof.

I claim:

The ornamental design for a jig block for hand-held shears, substantially as shown.
